UNITED STATES PATENT OFFICE.

WILLIAM A. TISCHENDORF, OF LEAVENWORTH, KANSAS.

IMPROVEMENT IN VALVES FOR BRASS MUSICAL INSTRUMENTS.

Specification forming part of Letters Patent No. **179,372**, dated June 27, 1876; application filed May 9, 1876.

To all whom it may concern:

Be it known that I, WILLIAM A. TISCHENDORF, of the city and county of Leavenworth, Kansas, have invented a new and useful Improvement in Musical Instruments, of which the following is a specification:

My invention relates to the cylinder-valves of wind-instruments to open and close the air-passages; and it consists of said cylinders, pivoted on center-points adapted to be adjusted from time to time to take up the slack, and being adjusted to spring-pressure, the object being to prevent the wear of the cylinders against the sides of the case, as they now do as soon as the journals wear a little.

Figure 1 is a side elevation of part of a wind-instrument having cylinder-valves, which are the subject of my invention. Fig. 2 is a sectional elevation on line *xx*, Fig. 3; and Fig. 3 is a horizontal section of Fig. 2, on line *yy*.

Similar letters of reference indicate corresponding parts.

A represents the cylinder-valves, which are commonly arranged on journals *B*, for which there is no adjustment when they wear, in

consequence of which the cylinders wear in certain parts of the sides against the case, and are very soon useless. I therefore propose to pivot these cylinders on centers *D E*, with provision for taking up wear by a screw, *F*, and with a spring, *G*, to regulate the pressure of the centers, and I will, in practice, fit the centers to run in jewels *H*, for greater durability.

These cylinders wear out in four or five years in the ordinary arrangement; but with my improvement there is practically no wear on the sides calculated to injure the efficacy of the cylinders for stopping the air.

Having thus described my invention, I claim as new and desire to secure by Letters Patent—

The cylinder-valves *A* of wind-instruments, fitted on centers *D E*, which are adjustable, and regulated by spring-pressure, substantially as specified.

WILLIAM ADAM TISCHENDORF.
